UNITED STATES PATENT OFFICE.

CHARLES W. MOWEN, OF PLAINFIELD, NEW JERSEY.

DESIGN FOR A PAPER-CLIP.

SPECIFICATION forming part of Design No. 34,060, dated February 12, 1901.

Application filed January 19, 1901. Serial No. 43,955. Term of patent 7 years.

To all whom it may concern:

Be it known that I, CHARLES W. MOWEN, a citizen of the United States, and a resident of Plainfield, in the county of Union and State of New Jersey, have invented and produced a new and original Design for a Paper-Clip, of which the following is a full, clear, and exact description.

Reference is to be had to the accompanying drawings, forming a part of this specification, in which similar characters of reference indicate corresponding parts in both the views.

Figure 1 is a front view of a paper-clip, showing my design; and Fig. 2 is a side view thereof.

The leading feature of my design for a paper-clip consists of the body portion having opposite side members longitudinally curved and joined at the top, with the lower ends turned inward and rearward and connected with a twisted tang having a longitudinal curve reverse to that of the body members and terminating in a ring or eye.

Referring particularly to the drawings, 1 designates the parallel side members of the 25 body, having a curved connection 2 at the top, while the lower ends are turned inward and rearward and are twisted together to form the upwardly-extending tang 3, which has a portion of its length curved outward between 30 the body members, which are also longitudinally curved.

Having thus described my invention, I claim as new and desire to secure by Letters Patent—

The design for a paper-clip as herein shown and described.

In testimony whereof I have signed my name to this specification in the presence of two subscribing witnesses.

CHARLES W. MOWEN.
